UNITED STATES PATENT OFFICE

GUSSIE F. RAYMOND, OF CICERO, ILLINOIS, ASSIGNOR TO WESTERN ELECTRIC COMPANY, INCORPORATED, OF NEW YORK, N. Y., A CORPORATION OF NEW YORK

TELEPHONE SYSTEM

Application filed March 11, 1932. Serial No. 598,199.

This invention relates to telephone systems, and more particularly to a device for optionally indicating a call at a called subscriber's set made during his absence.

5 An object of the invention is to provide a simple and effective device for indicating a call made during a called party's absence.

In its general aspects, the invention contemplates the use of a call-back indicator at 10 the subscriber's station and the employment of a call-back operator at a central station. When a calling party finds that the called party is absent and does not answer the telephone, he notifies the operator if he wishes 15 the called party to call back upon the called party's return. The operator then connects the calling subscriber to the call-back operator or secretary who makes note of the calling subscriber's name and telephone number 20 and actuates the call-back indicator at the called subscriber's set. Then upon the called subscriber's return, the called subscriber observes that the call-back indicator of his telephone set has been actuated and he calls 25 the call-back operator to learn the name and telephone number of the party who called during his absence. He may then call the party in the usual manner.

It is believed that a complete understanding of the invention may be had by reference to the following description taken in conjunction with the accompanying drawing, the single figure of which is a circuit diagram of a telephone system embodying the invention.

The invention may be embodied in a conventional telephone system having a cord circuit 4 provided with an answering plug 5 and a calling plug 6. The calling plug may be 40 associated with a jack 7 from which lines 8-8 lead to a subscriber's telephone 9. The telephone 9 may have a conventional circuit and is provided with a ringer 11 connected at one side to the junction point of a condenser 45 12 and the secondary of transformer 13. The other side of the ringer is connected to ground at 14.

A call-back indicator 15 is associated with the subscriber's set and may be located in any 50 convenient position; for example, the operat-

ing mechanism thereof may be located in the ringer box in such a position that an indicator plate 16 thereof will project from the box when in actuated position. The operating mechanism of the call-back operator has a 55 lever 17 pivotally mounted at 18 on a base 23 and the other end of the lever carries a pin movable in a slot 19 in plate 16. A second lever 21 is pivotally connected to lever 17 and also at one end to plate 16. The other end 60 of lever 21 carries a pin movable in a slot in the base 23. Lever 21 of the call-back indicator carries a projection 24, which is adapted to engage behind a similar projection on an armature 25 of a relay 26 when the indicator 65 is in its lower or retracted position. The engagement of these projections holds the indicator in its lower position against the tension of a spring 27.

The coil of relay 26 is connected at one side 70 to one of the lines 8 and at the other side through a condenser 28 to ground 14.

The operation of the system is as follows: When a calling subscriber calls a party, the operator inserts the plug 6 in jack 7 of the 75 called party's line and actuates a key 31 to disconnect the tip and ring of plug 6 from the cord circuit and connect the ring to a source of alternating current 32, which is grounded on one side at 33. The source then 80 supplies ringing current over the ring of plug 6 through condenser 12, ringer 11, to ground 14. If the called party fails to respond, the operator notifies the calling party of this fact and if the calling party wishes 85 the called party to call back, the operator connects the calling party to a call back operator who notes the name and telephone number of the calling party. The call-back operator then inserts a plug 30 in a multiple jack 90 37 of the called party's line and actuates a key 34 which connects the tip of jack 30 to the source of energy 32. This supplies current through the tip of plug 30 to the winding of relay 26 to condenser 28 to ground 14, 95 thereby retracting armature 25 and allowing spring 27 to raise the indicia plate 16 of the call-back indicator to its upper position. This will notify the absentee called party upon his return that someone has called 100

- during his absence. Upon the return of the called party, he notes that his call-back indicator has been operated and returns it to normal by merely depressing the indicia 5 plate 16. He then calls the call-back operator to learn the name and telephone number of the party who called during his absence, whereupon he may call the party who called during his absence.
- 10 It is evident that the nature and embodiment of the invention herein described and illustrated is merely illustrative of the invention and that many changes and modifications may be made therein without departing 15 from the spirit and scope of the invention.

What is claimed is:

1. In a telephone system, a telephone set having a ringer and call-back indicator, a talking circuit, said ringer and call-back indicator being connected in series and across the talking circuit, a ground connection between the ringer and call-back indicator, and means utilizing one portion of the talking circuit for actuating the ringer and another portion of the talking circuit for actuating the call-back indicator.
  2. In a telephone system, a telephone set having a ringer and a call-back indicator, a source of energy, and means for selectively energizing the ringer or call-back indicator from said source of energy.
  3. In a telephone system, a telephone set having a ringer and a call-back indicator, a talking circuit, a source of energy, means for energizing the ringer over a portion of said talking circuit from said source of energy, and means for energizing the call-back indicator over a portion of said talking circuit from said source of energy.
- 40 In witness whereof, I hereunto subscribe my name this 29th day of February 1932.

GUSSIE F. RAYMOND.
